(57) **CLAIM**

The ornamental designs for tire balancers (weights), as shown and described.

DESCRIPTION

FIG. 1 is a perspective view of a first embodiment including a chain of balancing weights joined by a mounting strip;

FIG. 2 is a top view of the first embodiment;

FIG. 3 is a left side view of the first embodiment, the right side view being a mirror image thereof;

FIG. 4 is a first end view of the first embodiment, the second end view being a mirror image thereof;

FIG. 5 is a perspective view of a second embodiment including a single balancing weight and portion of the mounting strip of the first embodiment;

FIG. 6 is a top view of the second embodiment;

FIG. 7 is a first end view of the second embodiment, the second end view being a mirror image thereof;

FIG. 8 is a left side view of the second embodiment, the right side view being a mirror image thereof;
FIG. 9 is a perspective view of a third embodiment including a chain of balancing weights joined by a mounting strip;
FIG. 10 is a top view of the third embodiment;
FIG. 11 is a left side view of the third embodiment, the right side view being a mirror image thereof;
FIG. 12 is a first end view of the third embodiment, the second end view being a mirror image thereof;
FIG. 13 is a perspective view of a fourth embodiment including a single balancing weight and portion of the mounting strip of the third embodiment;

FIG. 14 is a top view of the fourth embodiment;
FIG. 15 is a first end view of the fourth embodiment, the second end view being a mirror image thereof; and,
FIG. 16 is a left side view of the fourth embodiment, the right side view being a mirror image thereof.
All other surface(s) or portion(s) of the tire balancers not shown in the figures or otherwise described in the specification form no part of the claimed design.
